SAM CENTOFANTI AND ANNIBALE MARCHETTI, OF YOUNGSTOWN, OHIO

RADIATOR CAP AND MOVABLE HEADLIGHT

Application filed April 20, 1929. Serial No. 356,780.

This invention relates to improvements in movable lights adapted for use upon motor vehicles and the like.

An object of the invention contemplates supporting arms for the lights having swivel connection therewith.

Another object of the invention comprises rod members operatively connecting the connections of the lamp with the supporting arms to tilt and shift the lights to occupy desired positions.

An additional object of the invention consists in the provision of an operating member common to both the tilting and shifting rods whereby both motions may be simultaneously imparted to the lights.

With the above and other objects in view, the invention further consists of the following novel features and details of construction, to be hereinafter more fully described, illustrated in the accompanying drawings and pointed out in the appended claims.

In the drawings:—

Figure 1 is a front elevation of a motor vehicle equipped with the present form of light.

Figure 2 is a sectional view taken through a radiator cap and illustrating the connection of the arms and relative arrangement of the rod members.

Figure 3 is a longitudinal sectional view taken on line 3—3 of Figure 2.

Figure 4 is a sectional view taken on line 4—4 of Figure 2.

Figure 5 is a horizontal sectional view taken on line 5—5 of Figure 4.

Figure 6 is a front elevation of the dial face for the operating lever, the rheostat for the lights and inclinometer.

Figures 7 and 8 are detail sectional views taken through different forms of operating members for the lamp shifting rods.

Referring to the drawings in detail, wherein like characters of reference denote corresponding parts, the reference character 10

indicates the body portion of a radiator cap adapted for threaded connection with a radiator neck 11 substantially as illustrated in Figure 2 of the drawings. A closure cap 12, carrying an ornament 13 of any suitable design, is hingedly mounted, as at 14, to the upper periphery or mouth of the body portion of the cap. Supporting arms 15, of hollow formation, are extended laterally in oppositely disposed relation upon diametrically opposite sides of and having communication with the interior or bore of the radiator cap body as illustrated in the aforementioned figure.

A shaft 16, passed through the arms and body of the radiator cap, is bearingly mounted adjacent its ends for rocking movement within apertured bracket arms 17 carried upon the inner side walls of the supporting arms 15. Yoke members 18, carried upon the extremities of the shaft 16, are adapted to accommodate the balls 19 formed upon the innermost ends of extensions 20 carried upon the innermost ends of lamp casings 21, said yokes being adapted for pivotal connection with the balls 19. The extensions project through the openings 22 in the forward side walls of the supporting arms 15 as manifest from the illustration of our invention in Figure 3 of the drawings. Bars 23 and 24 respectively, mounted for oscillatory movement within ears 25 located upon the inner side walls of the supporting arms 15, terminate to provide rack teeth 26 upon the adjacent faces of the innermost ends thereof.

The bar 24 is provided with an L-shaped innermost end 27 whereby the teeth thereon may be disposed in spaced relation and in parallelism with the teeth upon the companion end of the bar 23 to effectively accommodate a gear member 28 therebetween. Retaining plates 29, carried upon the opposed sides of the gear 28 and having the peripheries thereof extending for appreciable dis-

tances beyond the circumference of the gear, are adapted to align the toothed ends of the bars 23 and 24 for meshing engagement with the gear.

5 Segments 30, of arcuate shape, are provided upon the innermost ends of the balls 19 and which are adapted for engagement with square threads 31 embossed upon the outer side walls or surfaces of the bars 23 10 and 24 upon the outermost projecting ends thereof.

An operating rod 32, common to both the shaft 16 and bars 23 and 24, is extended and projected through the body portion of the 15 radiator cap, the gear 28 being fitted upon a squared portion 33 adjacent the outermost end of the operating rod. Square threads 34, horizontally and circumferentially disposed in spaced relation upon the forward end of 20 the operating rod 32, are adapted for meshing engagement with the gear member 35, preferably located and keyed or otherwise fixed at an intermediate point in the length of the shaft 16.

25 The innermost end of the operating rod 32 is formed with a multiplicity of circumferentially arranged ribbed portions between which a spring pressed finger 37 is adapted for selective reception after the operating rod is extended and retracted through a horizontally disposed opening in the instrument panel 38 for a motor vehicle, substantially as illustrated in Figure 4 of our drawings. A handle member 39, included upon the innermost end of the operating rod 32, is located within convenient reach of the motor vehicle driver. A pointer hand 40, carried by the handle 39, is adapted to be shifted across the face of a dial 41 whereby the angularity of the lights 21 with respect to the vehicle may be readily apprehended.

From the foregoing description and accompanying drawings it is obviously apparent that shifting movement of the operating rod 32 will cause the lights 21 to be shifted or tilted upwardly and downwardly whereas rotation of the operating rod in either direction will cause the lights to be oscillated across the roadway to narrow or widen 45 the beam of light thrown in advance thereof.

In Figure 7 of our drawings, we have illustrated a modified form of gear member, such as indicated at 42, and which may be employed in place of the gear member 28. 55 The gear member 42 is not provided with retaining plates 29 but the teeth therefor are sunk within a channeled raceway 43 in the outer periphery thereof. Bars 44 and 45 operable by said gear are therefore provided with tooth portions adapted to be projected within the channeled raceway 43 for meshing engagement with the teeth therein. This construction is optional to that as disclosed in Figure 8 of our drawings.

65 The invention is susceptible of various

changes in its form, proportions and minor details of construction, and the right is herein reserved to make such changes as properly fall within the scope of the appended claims.

Having thus described the invention, what is claimed is:—

1. A movable headlight construction comprising laterally disposed arms having communication with the interior thereof, lamps for the arms having swivel connection therewith, a shaft establishing connection between the mountings for the lamps, segments carried by said mountings, bars having tooth portions upon the ends thereof adapted for engagement with the segments, an operating rod, and gear members carried upon the shaft and operating rod to provide a common control means whereby the lamps may be collectively and simultaneously tilted and laterally shifted respectively. 70

2. A movable headlight construction comprising a hollow body having laterally disposed arms of like construction in communication with the interior thereof, lamps having swivel connection within the ends of the arms, a shaft within the arms and body adapted for connection at its ends with the mounting for the lamps, bars mounted for oscillatory movement within the arms and having squared threads upon the outermost ends thereof, segments carried upon the lamp mountings adapted for meshing engagement with the square threaded portions of the bars, an operating shaft mounted within the body adjacent the shaft and bars, a gear carried by the rod within the body, the innermost ends of the bars being toothed and engaged with said gear, the foremost end of the operating rod having squared threads, and a gear member included upon the shaft engageable with the squared threads upon the operating rod whereby simultaneous shifting and rotary action imparted to the latter will effect synchronization with relation to said lamps. 90

3. A movable headlight construction comprising a hollow body having laterally disposed arms of like construction in communication with the interior thereof, lamps having swivel connection within the ends of the arms, a shaft within the arms and body adapted for connection at its ends with the mounting for the lamps, bars mounted for oscillatory movement within the arms and having squared threads upon the outermost ends thereof, segments carried upon the lamp mountings adapted for meshing engagement with the square threaded portions of the bars, an operating shaft mounted within the body adjacent the shaft and bars, a gear carried by the rod within the body, the innermost ends of the bars being toothed and engaged with said gear, the foremost end of the operating rod having squared threads, a gear member included upon the shaft engageable with the 100

squared threads upon the operating rod whereby simultaneous shifting and rotary action imparted to the latter will effect synchronization with relation to said lamps, ribs 5 included upon the operating shaft, and a spring pressed pin adapted for selective reception between the ribs to retain said rod against displacement.

In testimony whereof we affix our signatures.
